(57) **CLAIM**

The ornamental design for an e-book reader case, as shown and described.

DESCRIPTION

FIG. 1 is a front-elevational view of the e-book reader case of the invention in a closed condition;

FIG. 2 is a left side-elevational view thereof;

FIG. 3 is a right side-elevational view thereof;

FIG. 4 is a top-plan view thereof;

FIG. 5 is a bottom-plan view thereof;

FIG. 6 is a rear-elevational view thereof with a strap in an outer position;

FIG. 7 is a front and top-perspective view thereof in an open position;

FIG. 8 is a front and top-perspective view thereof with the strap in the outer position;

FIG. 9 is a rear and top-perspective view thereof with the strap in an inner position for holding an e-book reader;

FIG. 10 is a rear and bottom-perspective view thereof with the strap in the inner position;

FIG. 11 is a rear and top-perspective view thereof with the strap in the outer position; and,

FIG. 12 is a rear, top and side-perspective view thereof with the strap in the outer position and a front cover folded into a stand and engaged into a groove in a rear cover.

In the drawings, the broken lines show detail that form no part of the claim.
